UNITED STATES PATENT OFFICE.

GEORGE CODISH, OF BROOKLYN, NEW YORK.

DESIGN FOR A SANDAL-UPPER.

56,801.

Specification for Design. Patented Dec. 28, 1920.

Application filed May 10, 1920. Serial No. 380,423. Term of patent 14 years.

To all whom it may concern:

Be it known that I, GEORGE CODISH, a citizen of Russia, residing at Brooklyn, in the county of Kings and States of New York, have invented a new, original, and ornamental Design for a Sandal-Upper, of which the following is a specification, reference being had to the accompanying drawing, forming part thereof.

The figure is a plan view of the sandal upper.

I claim:—

The ornamental design for a sandal upper, as shown.

GEORGE CODISH.
